(57) CLAIM

The ornamental design for a mug, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of the mug showing our new design;

FIG. 2 is a rear perspective view of the mug;

FIG. 3 is a front view of the mug;

FIG. 4 is a rear view of the mug;

FIG. 5 is a right side view of the mug;

FIG. 6 is a left side view of the mug;

FIG. 7 is a top view of the mug; and,

FIG. 8 is a bottom view of the mug.
